UNITED STATES PATENT OFFICE.

CYRUS A. HOVEY, OF PORT HURON, MICHIGAN, ASSIGNOR TO JOHN H. WHETSTONE, OF LAPEER, MICHIGAN.

AUTOMOBILE-JACK.

1,249,757.

Specification of Letters Patent. Patented Dec. 11, 1917.

Application filed August 8, 1913. Serial No. 783,687.

To all whom it may concern:

Be it known that I, CYRUS A. HOVEY, a citizen of the United States, residing at Port Huron, in the county of St. Clair and State 5 of Michigan, have invented certain new and useful Improvements in Automobile-Jacks, of which the following is a specification.

My invention has in view a device of this character which may be rapidly and readily 10 applied to the axles of automobiles to be worked upon and as readily removed therefrom, which is applicable to machines having a wide range of variation in the height of their axles and which is simple and inexpensive and easily manipulated.

In the accompanying drawing I have illustrated the preferred form of my invention for the purpose of exemplifying the same, but it is to be understood that it is not limited to this particular embodiment 20 but may be widely varied within the scope of the following claims in which I have endeavored to distinguish it from the prior art so far as known to me without, however, 25 relinquishing or abandoning any portion thereof. The drawing which accompanies and forms a part of the application illustrates my invention in side elevation.

In the particular embodiment illustrated 30 the main frame consists of a handle and a guide which are preferably formed integral in a single casting. The guide 1 is skeleton in construction and is substantially perpendicular to the handle 2 at the point of union 35 and a brace 3 also cast integral serves to provide additional strength. Arbors or axles 4—4 are formed integral with the main casting projecting on opposite sides thereof at a point approximately at the angle of 40 the guide and handle. It will be seen that the handle is curved upwardly away from the jack and the wheels 5, 5 mounted upon the arbors are of such size that they support the inner or angle end of the handle above 45 the ground, thus forming with the handle a 3-point support when the jack is in working position. The angular relation of the guide to the handle is such that when in this position the upper or supporting end of the jack 50 is in a plane intermediate the axle and the point of the handle in contact with the floor or ground so that the axle is stably supported. The adjustable post 6 of the jack is also formed of a single casting and of a size 55 and shape to fit within the guide member

of the frame and to readily slide therein. At its upper end the post member is provided with a crotch or head 7, the upper surface of which is formed on a compound curve. The forward end 8 inclines downwardly and the rear end 9 upwardly, as clearly shown in the drawing. In the particular embodiment of the invention illustrated the guide is substantially rectangular in cross-section to prevent rotation of the 60 sliding post with reference thereto and near its upper end is enlarged laterally into a chamber 10, the bottom and top walls of which are inclined and which receives the oblong link-shaped pawl 11. The latter is 65 hung at its upper or rearward end upon a lug 12 forming substantially a portion of the wall of the guide and is maintained in position by an ear 13 also cast integral with the frame structure and which may, if desired, 70 be cast to permit the insertion of the pawl into position and subsequently bent over to retain the same, the casting being of sufficiently malleable material for this purpose. At its forward end the pawl is formed 75 with a lip which constitutes a convenient manipulating means and may be operated either by the hand or by the toe of the person using the jack. The sliding post is suitably toothed or formed with a rack on its 80 forward edge as shown at 14 to coöperate with this pawl and when it is desired to lower the post the pawl may be raised and the post drops to its normal position.

The manner of using the jack will now be 85 readily apparent. The adjustable post is raised to the extent necessary for use in connection with the particular automobile axle to be handled and the handle raised to tilt the post rearwardly so that the jack may be 90 backed under the axle, the handle is then lowered and the axle received within the crotch or curved head of the post, where by reason of the form of said head it slips forwardly into position immediately over the 95 post. When in this position the weight is so far forward of the wheels that if by any accident or otherwise the automobile is shifted rearwardly with respect to the jack the latter rolls upon its wheels without unshipping 100 the axle from the crotch. The down-turned end on the head of the sliding post is for the purpose of convenient manipulations by the hand or foot of the operator. The handle 105 may be formed as a single piece integral with 110

the frame but preferably for convenience in shipment I form the same in two sections as shown in the drawing, each section being recessed or cut away upon one side and formed with an extended tongue on the other, the tongue upon one member overlapping and fitting into the recess of the other member and the sections secured by transverse screws, bolts or rivets.

- 10 It will be seen that my jack may be applied to an automobile by the simple operation of moving it into the proper position with the handle lifted and then lowering the handle into contact with the floor or ground, and may be removed from the automobile by simply reversing this operation.

I claim:

1. An automobile jack comprising a handle, a guide extending substantially perpendicular thereto, and having a longitudinal guide-way and enlarged chamber, a post ad-

justable in said guide-way and having a rack upon one face thereof, a bearing formed upon one wall of the guide, a closed loop journaled in the bearing extending through the chamber and completely surrounding the post, and engaging the rack thereon.

2. An automobile jack comprising a handle, a guide extending substantially perpendicular thereto, and having a longitudinal guide-way and enlarged chamber, a post adjustable in said guide-way and having a rack upon one face thereof, a bearing formed upon one wall of the guide, a closed loop journaled in the bearing, extending through the chamber and completely surrounding the post, and a finger piece formed on the loop for raising the same.

CYRUS A. HOVEY.
